UNITED STATES PATENT OFFICE.

HENRY R. KOHLWEYER, OF PITTSBURG, PENNSYLVANIA.

BUTTON.

No. 890,364.

Specification of Letters Patent.

Patented June 9, 1908.

Application filed October 10, 1907. Serial No. 396,741.

To all whom it may concern:

Be it known that I, HENRY R. KOHLWEYER, a citizen of the United States, residing at Pittsburg, Allegheny county, Pennsylvania, have invented certain new and useful Improvements in Buttons, of which the following is a specification, reference being had therein to the accompanying drawings.

This invention relates to buttons, and 10 more particularly to that type of buttons having a tilttable or movable head, such for instance as "collar and cuff buttons."

The primary object of my invention is to provide a button of the above type wherein 15 positive and reliable means are employed for retaining the tilttable head of the button in a closed or parallel position with relation to the body of the button.

Another object of the invention is to provide a button having a tilttable or movable head that can be moved into a plane approximately horizontal of the shank of the button.

With these objects in view, the invention will now be described in detail.

In the drawings: Figure 1 is a vertical sectional view of a button constructed in accordance with my invention, Fig. 2 is a vertical transverse sectional view of a button.

The button comprises a circular body 1 having a tapering shank 2. The circular body is recessed, as at 3, to accommodate a metallic diaphragm 4, said diaphragm being retained within the circular body 1 by a ring 5 threaded in said body, as at 6.

The shank 2 is provided with a bore 7 and movably mounted in said bore is a rod 8 carrying at its lower end a cup 9. This cup 9 is normally retained in engagement with the diaphragm 4 by a spring 10 surrounding the

rod 8. The cup 9 prevents the end of the rod 8 from injuring or puncturing the diaphragm 4, which is preferably made of light and resilient sheet metal. The upper end of the rod 8 is bent to provide a hook 11 for engaging a stirrup 12 carried by the head 13 of the

button. The head 13 is made of light and durable metal which is pressed into the form of a cap adapted to shield and house the stirrup 12 and the upper end of the rod 8. The head 13 besides being connected to the rod 8 is pivotally connected by a stirrup 14 to a stationary rod 15, carried by the shank 2. In order that the head 13 can assume a plane approximately horizontal with the shank 2, I

have recessed said shank 2, as at 16, to receive the edge of the head when tilted.

The spring 10 is employed to normally maintain the head 13 in a closed position, approximately parallel with the body of the button, the tension of said spring exerting a downward pressure upon the rod 8 in excess of the upward pressure of the diaphragm 4, consequently said diaphragm is normally held under tension. This diaphragm is employed to assist in retaining the head 13 in a closed position, it only being necessary to press upon the diaphragm, or to tilt the head to overcome the tension of the spring 10.

Due to the fact that the head 13 is pivoted at one side of the vertical axes of the shank 2, it will be observed that when the head is tilted and the stirrup 11 thus moved to a point above the stirrup 12, a slight pressure of the diaphragm 4 will be sufficient to retain said head in open position, but this pressure is easily overcome by slightly moving the head 13, which is immediately closed by the pressure of the spring 10 upon the lower end of the rod 8. By the novel construction of the button just described, it will be observed that the head of the button can be opened by pressing upon the diaphragm 4 of the body of the button. This feature is of convenience when the button is in the button hole of a shirt band, and the ends of a collar are to be placed upon the shank of a button.

Having now described my invention what I claim as new, is:—

1. A button embodying a circular recessed body, a shank carried thereby, a diaphragm mounted in said recessed body, a rod movably mounted in said shank, a spring surrounding said rod within said recessed body, a tilting head pivotally mounted upon the end of said shank, a stirrup carried by said head and connecting with said rod, said shank having a recess formed therein for receiving the edge of said head when said head is tilted.

2. A button comprising a recessed body having an integral shank, a diaphragm arranged in said body, a rod extending through said shank, a tilting head pivotally mounted upon said shank and connecting with said rod, said shank having a recess formed therein to receive the edge of said head, and means arranged within said body for normally holding said head parallel thereto.

3. A button comprising a body provided with a recess, a shank carried by said body, a rod extending through said shank, a head provided with a stirrup with which said rod is operatively connected, a diaphragm secured within the recess of said body, a cup carried by the lower end of said rod and bearing against said diaphragm, and a spring ar-

ranged on the rod for normally holding the diaphragm in extended position.

In testimony whereof I affix my signature in the presence of two witnesses.

HENRY R. KOHLWEYER.
